(57) **CLAIM**

The ornamental design for a fume hood with an angled front, as shown.

DESCRIPTION

The fume hood includes a hood body, a sliding door or sash, a work surface, an airfoil, an exhaust plenum, and baffles to maintain airflow uniformity. The fume hood serves to control exposure to toxic, offensive or flammable vapors, gases and aerosols in the laboratory by exhausting the same from a confined location, helping to protect workers from inhalation exposure.

FIG. 1 is a front view of the fume hood with an angled front; FIG. 2 is a first side view of the fume hood with an angled front;

FIG. 3 is a second side view of the fume hood with an angled front;

FIG. 4 is an enlarged top view of the fume hood with an angled front;

FIG. 5 is an enlarged rear view of the fume hood with an angled front;

FIG. 6 is a first perspective view of the fume hood with an angled front;

FIG. 7 is an enlarged perspective view of the detail 7 from FIG. 6;

FIG. 8 is an enlarged second perspective view of the fume hood with an angled front; and,

FIG. 9 is an enlarged perspective view of the detail 9 from FIG. 8.
